US00D954687S

(12) **United States Design Patent** (10) **Patent No.:** **US D954,687 S**
Mai (45) **Date of Patent:** **** Jun. 14, 2022**

(54) **MICROPHONE**

(71) Applicant: **SHENZHEN XUNWEIJIA TECHNOLOGY DEVELOPMENT CO., LTD.**, Shenzhen (CN)

(72) Inventor: **Qibin Mai**, Shenzhen (CN)

(73) Assignee: **SHENZHEN XUNWEIJIA TECHNOLOGY DEVELOPMENT CO., LTD.**, Shenzhen (CN)

(**) Term: **15 Years**

(21) Appl. No.: **29/786,362**

(22) Filed: **May 31, 2021**

(51) LOC (13) Cl. **14-01**

(52) U.S. Cl.

USPC **D14/229; D14/226**

(57) **CLAIM**

The ornamental design for a microphone, as shown and described.

DESCRIPTION

FIG. 1 is a front, right side, top perspective view of a microphone showing my new design;

FIG. 2 is a rear, left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depict portions of the microphone that form no part of the claimed design.

1 Claim, 8 Drawing Sheets
